UNITED STATES PATENT OFFICE.

GEBHARD JAEGER, OF COLUMBUS, OHIO.

LOADER FOR CONCRETE-MIXERS.

1,262,052.

Specification of Letters Patent. Patented Apr. 9, 1918.

Application filed February 8, 1915. Serial No. 6,700.

To all whom it may concern:

Be it known that I, GEBHARD JAEGER, a citizen of the United States, residing at Columbus, in the county of Franklin and State 5 of Ohio, have invented a certain new and useful Improvement in Loaders for Concrete-Mixers, of which the following is a specification.

The object of this invention is more especially to provide improved means for automatically loading or charging concrete mixers with materials to be mixed whereby that work can be accomplished with greater convenience, cleanliness and more 15 speed and with less manual labor than heretofore.

The invention is embodied in the example illustrated in the accompanying drawing, set forth in the following specification and 20 finally claimed.

In the said drawing—

Figure 1 is a side elevation showing the apparatus in full lines with the bucket lowered and in broken lines the bucket elevated 25 to discharge into the mixing drum.

Fig. 2 is a front elevation.

In the views 5 designates the mixing drum which has suitable means for tilting and rotating it, said means being unnecessary 30 to detail here. The mixing drum is shown as mounted on a suitable truck and frame including a standard 6 and platform 7. Erected from the platform is a frame 8 for receiving the pulleys and other parts employed in the construction.

9 designates the bucket which has a bail 10 hinged thereto at opposite sides as at 11. The bucket tapers toward its discharging end so that ordinary loading will leave it 40 substantially balanced on the hinging points 11. Connecting the bucket at the hinges 11 and the standard 6 at the points 6^a of the standard are arms 12 that are transversely connected by curved straps 13 reaching under the bucket. The arms 12 and straps 13 45 form a sort of cradle to support the discharging end of the bucket. The bucket together with its supporting cradle are hoisted by means of a cable 14 that is attached to 50 the bail 10 and passes first to and over a pulley 15 on the frame 8, thence to and

under a pulley 16 on the bail 10, thence to and over two pulleys 17 and 18 to a suitable hoisting drum 19. Hinged to and depending from the frame 8 is an arm 24 having a 55 guiding finger 20 and hook 21. Normally the guiding finger 20 lies in the path of a bar 22 subtending the sides of the bucket across the top so that when the bucket is raised, the bucket being loaded to balance 60 on the bail, the hook engages the bar 22 and holds said discharging end depressed while the other end is carried up and the discharging end directed toward the mouth of the mixing drum, as illustrated in the 65 upper of the broken line positions of the bucket Fig. 1. The lower broken line position of the bucket illustrates the position of that member at the moment when the bar 22 strikes the guiding finger 20. It will be 70 observed that because the bucket maintains its original balanced position until the bar 22 strikes the finger 20, the said bar does not when the bucket is elevated, travel upon an arc of a circle having for its center the 75 hinging points 6^a but rather upon a curve eccentric to said hinging points. In the operation the arm bearing the hook 21 swings toward the mouth of the mixing drum so as to bring the discharging end of 80 the bucket very near or into the mouth of the drum whereby practically the whole of the load is discharged into the mixing drum without spilling upon the platform or machinery.

When the cable winding drum is turned in the direction opposite that employed for winding up the cable the bucket and its guiding and supporting cradle fall to the 85 ground for reloading.

The parts of the construction can be 90 changed without departing from the invention as claimed.

What I claim is—

1. A loader for a concrete mixer comprising in combination, a frame, arms pivoted to the frame, a bucket tiltably secured to said arms, means for hoisting the bucket and an arm pendentively pivoted to the frame, said arm having a guiding finger and a hook to 95 engage the bucket to cause the tilting of the same when hoisted.

2. A loader for a concrete mixer comprising in combination, a frame, arms pivoted to the frame, a bucket tiltably secured to said arms, means for hoisting the bucket and a pendent oscillating means to arrest the elevation of the discharge end of the bucket and cause the same to move substan-

tially horizontally toward the place of discharge.

GEBHARD JAEGER.
